United States Patent Office.

WILLIAM R. OATLEY, OF ROCHESTER, NEW YORK.

Letters Patent No. 97,431, dated November 30, 1869.

STOVE-LEG.

The Schedule referred to in these Letters Patent and making part of the same.

To all whom it may concern:

Be it known that I, WILLIAM R. OATLEY, of Rochester, in the county of Monroe, and State of New York, have invented certain new and useful Improvements in Stove-Leg Fastenings; and I do hereby declare that the following is a full, clear, and exact description thereof, reference being had to the accompanying drawings, making part of this specification, in which—

Figure 1 is an inverted view of my invention.

Figure 2 is a vertical section at the dotted line *x*, fig. 1.

Figure 3 is a similar section at the dotted line *y*.

Figure 4 is an inverted view of a modification of my device.

The object and nature of my invention will be understood by reference to the specification and drawings, and to enable others to make and use the same, I will describe its construction and operation.

The stove-leg *A* is made with the flange *a*, having bevelled edges, and fitting between the lugs *b*, provided upon the bottom plate of the stove, in the usual manner.

The flange *a* has a longitudinal slot, *c*, fig. 1, the edges of which are bevelled in an opposite direction to those of the flange *a*.

A lug *d*, is cast upon the bottom plate of the stove, fitted to slide in the slot *c*, as shown in fig. 2.

At the inner end of the slot *c*, an opening, *c'*, is provided, through which the lug *d* enters. The slot *c* is made somewhat narrower at the end farthest from

the opening *c'*, whereby the flange *a* is tightly bound to the stove-bottom, as the lug *d* is forced into the slot. The lugs *b* may also be somewhat inclined toward each other, outward, for a like purpose.

The leg *A* is secured by entering the lug *d* in the opening *c'*, as shown by dotted lines in fig. 1, and forcing the leg forward between the lugs *b*.

It will be observed, that the leg *A* cannot be pushed out by the weight of the stove or by any accidental jar, while the manner of attaching is not more expensive than the ordinary fastening. The lug *d* may be made with a T or circular head, as shown in fig. 4.

Instead of the bevelled lugs *b*, straight projecting spurs may be used, as shown in dotted lines in fig. 4, to keep the leg in line.

Instead of providing the opening *c'*, the lug may be made sufficiently narrow to enter the slot longitudinally, when the flange *a* is turned at right angles, whereby the leg cannot be removed without first forcing it from the lugs *b*, and giving it a quarter turn.

What I claim as my invention, and desire to secure by Letters Patent, is—

1. The dovetailed lug *d*, in combination with the slotted flange of the leg *A*, for the purpose set forth.

2. In combination with the side lugs *b*, the central lug *d*, arranged to act conjointly, for the purposes set forth.

WM. R. OATLEY.
